ATTORNEYS

UNITED STATES PATENT OFFICE.

GEORGE BOEHM, OF MARSHFIELD, WISCONSIN.

WOVEN-WIRE BED-BOTTOM.

No. 923,006.

Specification of Letters Patent. Patented May 25, 1909.

Application filed March 26, 1909. Serial No. 435,882.

To all whom it may concern:

Be it known that I, GEORGE BOEHM, a citizen of the United States, and a resident of Marshfield, in the county of Wood and State of Wisconsin, have made certain new and useful Improvements in Woven-Wire Bed-Bottoms, of which the following is a specification.

My invention relates to improvements in bed bottoms and more particularly to the class known as woven wire bed bottoms.

In order that two persons lying on a woven wire bed bottom of the usual construction may not roll or move toward the center of the bed, it is generally necessary that the central portion of the woven wire bottom be reinforced or rendered less flexible than the side portions of the bed bottom.

It is the object of this invention to provide an improvement in such bed bottoms by so constructing the bed bottom that the tension at the longitudinal center shall be stronger than at the sides, so that when two persons are occupying a bed having my improved woven wire bottom, they will not roll toward the center, and so that when one person is of a less weight than the other each can keep his position in bed without incommodeing the other.

My invention is embodied in the construction, arrangement and combination of parts as will be hereinafter fully described and pointed out in the claims, reference being had to the accompanying drawing in which—

Figure 1 is a top plan view of a bed bottom constructed in accordance with my invention; Fig. 2 is a vertical transverse section of the same; Fig. 3 is a transverse sectional view showing the operation of my improvement.

In the drawing is shown a bed bottom consisting of the usual side rails A and the end bar B, the end bars being secured upon the side rails by nails a screws or other suitable means; the end bars are made in two parts between which the ends of woven wire bottom C are clamped and held by nails or other suitable means; said woven wire fabric is turned upon itself at the side edges forming longitudinal pockets c within which is placed a rope D which serves to strengthen the edges.

The woven wire fabric is of a width somewhat greater than the distance between the side rails and the central portion is folded over upon itself in opposite directions form-

ing two flat folds C' C' and within the space formed between the upper surface of the bottom and the folded over portions longitudinal ropes E E are placed and retain the 60 folds in place after they are folded down flat on the bed bottom; this formation leaves the longitudinal central portion of the bed bottom slightly elevated. The strength of the woven wire fabric is such that the folds 65 will lie perfectly flat when no weight is on the bed bottom. If now a person should occupy one side of the bed, say the left side as indicated in Fig. 3, the weight of the person causes that portion of the fabric between the left side rail and the center of the bed to sag the left hand fold being drawn toward the center, and as the rope brace is immovable the under ply of the fold will slide around the rope brace and the left 70 hand portion of the bottom will assume a position similar to that shown in Fig. 3, thus the person occupying that side of the bed cannot roll toward the center. If both sides of the bed are occupied the same action 75 takes place on both sides of the center only in a less degree on each side and tending to equalize the strain.

I claim:

1. A bed bottom consisting of side rails 85 and end bars and a woven wire fabric continuous from side to side and folded upon itself to form a movable flat fold at its longitudinal center.

2. A bed bottom consisting of side rails 90 and end bars, and a woven wire fabric continuous from side to side and folded upon itself at its longitudinal center forming two independent spring sections on each side of said center.

3. A bed bottom consisting of side rails and end bars, a woven wire fabric secured to the end rails and folded upon itself at its longitudinal center, and longitudinal ropes located between the folded over portion and 100 the upper surface of the woven wire fabric.

4. A bed bottom consisting of side rails and end bars, a woven wire fabric secured to said end bars, said fabric bent to lie in a flat fold at each side of the longitudinal center, 105 and longitudinal ropes held within the space between said folds and the upper surface of the fabric bottom.

5. A bed bottom consisting of side rails and end bars, a woven wire fabric secured to 110 said end bars, the side edges of said fabric folded upon itself, a rope disposed within

said folded back edges, the central portion of the wire fabric bent to form a flat fold on each side of the longitudinal center of the bed bottom, and longitudinal ropes secured 5 at their ends to the end bars and lying between the flat folds and the upper surface of the wire fabric.

6. A bed bottom consisting of side rails and end bars and a woven wire fabric secured 10 to said end bars and of a width greater than the distance between the side rails the surplus width disposed to form a section extending on both sides of the longitudinal center of the bed bottom and lie in a flat 15 plane above that of the body portion of wire fabric.

7. A bed bottom consisting of side rails and end bars and a continuous woven wire fabric rigidly secured at its ends to said end bars, the width of said fabric being greater 20 than the distance between the side rails, the surplus being disposed to form a flat fold extending on both sides of the longitudinal center of the bed bottom, and each side section of the fabric bottom susceptible of independent deflection below the plane of the bed bottom. 25

GEORGE BOEHM.
